United States Patent Office.

GEORGE NEILSON, OF BOSTON, MASSACHUSETTS.

Letters Patent No. 75,960, dated March 24, 1868.

IMPROVEMENT IN LAMP-BURNERS.

The Schedule referred to in these Letters Patent and making part of the same.

TO WHOM IT MAY CONCERN:

Be it known that I, GEORGE NEILSON, of Boston, in the county of Suffolk, and State of Massachusetts, have invented certain new and useful Improvements in Lamp-Burners; and I hereby declare the following to be a full, clear, and exact description of the same, reference being had to the accompanying drawings.

My invention relates to the class of burners in which a deflector, elevated at some distance above the base of the burner, is combined with an air-supply cylinder, upon which it rests; and its object is, first, to produce a burner of this description, the component parts of which may be separated and detached from each other readily, thus facilitating the cleansing and repairing or manipulating of the burner; second, to afford increased security and support for the chimney, and so prevent it, as far as possible, from being detached or shaken from its seat by any sudden jar or shock.

The following are the essential characteristics of the invention, by which I have realized the above results.

First, the combination, with the wick-tube and air-supply cylinder, of a deflector, hinged to said cylinder.

Second, the combination, with the chimney-seat and wick-tube, of an air-supply cylinder, detachable or removable from its seat, and a deflector hinged to the air-supply cylinder.

Third, the combination, in a burner such as described, of a chimney-rest, air-supply cylinder, and deflector, when the said parts are capable of being removed from or applied to the burner, bodily and together.

Fourth, the combination, with the base and wick-tube, of a chimney-seat, air-supply cylinder, and deflector, when the said chimney-seat, cylinder, and deflector are removable or detachable from the base and wick-tube, and from one another.

Fifth, the combining with and attaching to the air-supply cylinder, springs, or equivalent devices, for steadyng the chimney.

Sixth, forming a bevelled seat for the chimney, whereby the latter is firmly held in position.

These, and other features of the burner in which my invention consists, will be readily understood by reference to the accompanying drawings, in which—

Figure 1 is a side elevation of the burner,

Figure 2 is a vertical central section, and

Figure 3 is a plan view of the same.

A represents the deflector, hinged at *a* to the top of the air-supply cylinder B, whose lower end fits around the raised cylindrical portion *b* of the chimney-rest D, which part *b* supports or carries the diaphragm or perforated air-distributer *c*, and the latter fits around the flat-wick tube C, preventing the rotation or displacement of the chimney-rest D, on which the air-supply cylinder and deflector depend for their support. The chimney-rest D is in turn supported on a bell-shaped or flaring frame, E, the lower and contracted or drawn-in end of which is secured to or forms part of the base or lamp-reservoir cap F. The frame E has a number of openings formed in it, which, in effect, divide the frame into a series of arms or standards, upon the top of which the plate D rests. The deflector is hinged to the cylinder by means of a small hook or bent arm, *a*, the end of which is inserted into a slit, *d*, of corresponding size, formed in the side of the cylinder, as shown in fig. 2. Upon the opposite side of the deflector is a spring-clasp, *f*, which, when the deflector is down, catches upon the cylinder, and thus holds the deflector firmly in place. The construction of the hinge-joint, just described, is such as to admit of the deflector being removed, and separated from the cylinder whenever desired. The cylinder can also be readily slipped on and off the part around which its lower end fits. Its position when fitted on the part *b* is determined by a lug, *e*, which fits in a recess, *g*, of like shape, in the cylinder. The latter is thus held in such position that the slot in the hinged dome will be accurately placed with respect to the wick-tube. The chimney-rest is likewise capable of being removed from or adjusted to the burner. The diaphragm *c*, which fits closely around the flat-wick tube, serves to steady the chimney-rest, and to prevent its lateral displacement, while the frame E supports it and the parts which it carries.

It will thus be seen that by lifting off the chimney-rest, the chimney, cylinder, and deflector will be removed bodily and together, while at the same time these parts can also be detached and taken apart from each other. All parts of the burner can, therefore, be readily handled and cleaned.

In order to more effectually hold the chimney in position, that portion of the rest D, which constitutes the chimney-seat k, is bevelled or inclined, as seen in figs. 1 and 2, so that when the base of the chimney is pressed down upon this bevelled or sloping surface, it will become in some measure jammed or wedged thereon, and will thus be held erect and firmly, and prevent the chimney from being accidentally tilted or shaken from its seat. A series of springs, or equivalent elastic and yielding devices, l, are attached to and project from the air-supply cylinder, so as to bear against the interior of the chimney, and thus contribute to its support.

By combining in this manner these necessary spring-devices with the cylinder, I am enabled to remove them readily from the burner with the cylinder, and thus leave the chimney-rest free to be manipulated or cleaned. The course of the air in the burner is indicated by the arrows in fig. 2. It enters the openings in the frame E, ascends through the air-distributing diaphragm e, and then passes out with the flame through the slot in the deflector, and through the apertures s formed in the top of the same.

The bevelled chimney-seat may be formed as shown in the drawings, or in any other ordinary or suitable manner. I have contemplated making the lower end of the air-supply cylinder flaring for this purpose, in which case the chimney-rest D may be dispensed with, and the air-distributing diaphragm e attached directly to the bottom of the said cylinder.

Having now described my invention, and the manner in which the same is or may be carried into effect, what I claim, and desire to secure by Letters Patent, is—

1. The combination, in a burner such as described, of the air-supply cylinder, with a deflector hinged to the said cylinder, substantially as and for the purposes herein shown and set forth.
2. The combination, with the chimney-rest and wick-tube, of an air-supply cylinder, detachable or removable from its seat, and a deflector hinged to the air-supply cylinder, substantially as and for the purposes herein shown and set forth.
3. The combination, in a burner such as described, of a chimney-rest, air-supply cylinder, and deflector, when the said parts are capable of being removed from and adjusted to the burner bodily and together, substantially as and for the purposes shown and specified.
4. The combination, with the base and wick-tube of a lamp-burner, of a chimney-rest, air-supply cylinder, and deflector, when the same are detachable from the said base and wick-tube, and from one another, substantially in the manner and for the purposes shown and described.
5. The combination, with the air-supply cylinder, of chimney-supporting springs, attached to and projecting from said cylinder, substantially as herein shown and described.

In testimony whereof, I have signed my name to this specification before two subscribing witnesses.

GEORGE NEILSON.
